INVENTOR
BY Victor J. Evans
ATTORNEY

UNITED STATES PATENT OFFICE

PETER JOSEPH FAGAN, OF HOMESTEAD, PENNSYLVANIA

ADJUSTABLE CURTAIN BLIND AND PORTIÈRE HOLDER

Application filed October 23, 1929. Serial No. 401,798.

This invention relates to window curtains, window blinds and portière brackets or holders, and has as one of its objects to provide, in a bracket of this class, a novel arrangement 5 of attachment members, and bracket members for supporting the curtain or shade rollers or rods, and one of the objects of the invention is to provide means whereby, upon the base or attaching member of the bracket, 10 various kinds of supporting members may be adjustably arranged, depending upon the character of the portière to be suspended, so that the device may be put to various uses.

Another object of the invention is to so 15 construct pairs of the brackets that the bracket members, which are to be mounted thereon, may be attached to and dismounted from the base without removing the base from the window or door frame.

20 This invention also consists in certain other features of construction and in the combination and arrangement of the several parts, to be hereinafter fully described, illustrated in the accompanying drawings, and specifically pointed out in the appended claims.

25 In describing my invention in detail, reference will be had to the accompanying drawings wherein like characters denote like or corresponding parts throughout the several 30 views, and in which:—

Figure 1 is a view in front elevation illustrating an arrangement of window brackets embodying the invention.

Figure 2 is a view in side elevation of one 35 of the brackets, the same being designed for the support of a shade roller and also a rod for supporting portières, or a curtain.

Figure 3 is a view showing the component parts of the invention in perspective the parts 40 being relatively separated.

Figure 4 is a perspective view of one of the brackets.

Figure 5 is a similar view illustrating another one of the brackets.

45 The base of each bracket is best illustrated in Figures 2 and 3 of the drawings and comprises a sheet metal plate 1 which is of rectangular form, and which has its upper and lower marginal portions overturned as indicated by the numeral 3, so as to provide flange

portions 3 which are spaced with respect to the side of the body of the plate 1, and the said plate 1 is formed with openings 4 for the passage of nails or screws, indicated by the numeral 5, so that the base may be positioned and secured to the window frame or door frame depending upon the use to which the device is to be put. At this point it will be evident that when the base plate 1 is secured to the face of a window frame or door 55 frame, the said plate will be somewhat spaced with respect to the face of the frame so that the heads 6 of securing bolts 7 may be accommodated in the space between the plate 1 and the face of the window or door frame, 60 these bolts being provided with wing nuts 8 and the plate being formed in one vertical edge with a relatively long slot 9 extending parallel to the lower edge of the plate and also in its said edge with the shorter slot 10 located near and parallel to the upper edge of the plate.

65 The numeral 11 indicates in general one of a pair of brackets for supporting a window shade roller and this bracket comprises 70 an attaching portion 12 having a slot 13 therein opening through the outer end edge thereof. The bracket further comprises a portion 14 extending at right angles from the opposite end of the portion 12 and provided with a notch 15 to receive the end of the 75 spring spindle of the shade roller.

80 As shown in Figure 2 and also in Figure 1, the portion 12 of the bracket 11 is disposed against the outer face of the plate 1 with the slot 13 registered with the slot 9 and the bolt 7 extending through the said slots, it being understood that the bolt 7 may be assembled with the plate 1 after the plate has been secured to the window frame and, inasmuch as the slot 13 in the portion 12 of the bracket 11 opens through the end of said portion, this member may likewise be fitted to the bolt after the base plate 1 has been mounted and, due to the provision of the slots, 85 the member 11 may be adjusted longitudinally of the base member depending upon the length of the shade roller.

90 As shown in Figure 1 of the drawings, that end of each base plate 1 in which the slots 100

- 9 and 10 are formed, may project beyond the outer side of the stile of the window frame to which it is secured, therefore the slot 10 may be located entirely beyond and clear of the said stile, and this permits of the use of the bracket member shown in Figures 2 and 3 and indicated in general by the numeral 16, the said bracket member comprising an attaching portion 17, which is flat and preferably rectangular, and from the opposite side edges of which project bracket arms 18, which are provided with slots 19 in which a shade or curtain supporting member may be engaged at its ends, a threaded stud 20 being provided upon the rear side of the portion 17 of the bracket 16 and fitted through the slot 10, and the thumb nut 21 being threaded upon the stem and tightened to hold the bracket member in place.
20. Figure 4 of the drawings illustrates another form of bracket which comprises an attaching plate 22 which plate is preferably rectangular and provided centrally with an opening 23 through which one of the bolts 7 may be engaged, and, in this embodiment of the invention, arms 24 are secured at their lower ends to the plate 22 and are provided with upstanding portions 25 to which the appropriate end of a curtain rod may be fitted, it being understood that this bracket member will be mounted, in the same manner as the bracket member 11, above referred to.
35. Figure 5 of the drawings illustrates a further modification in which a longitudinal attaching member 26 is provided at each end with an outstanding socket 27, and is formed midway between its ends with an opening 28 through which one of the bolts 7 may be fitted, these sockets being designed to receive the right angularly bent ends of a cylindrical curtain rod.
40. What I claim is:—
1. An adjustable curtain blind and portière holder comprising attaching members each including a rectangular shaped plate having portions thereof bent to provide flanges at the upper and lower edges of the plate for engagement with a support to space one face of the plate from said support and hold the plate against upward and downward movement relative to said support, fasteners extending through the plate into the support for securing the plate with one side edge thereof projected beyond one end of the support, said plate having slots extending through said side edge, headed fasteners received by the slots with the headed portions disposed between the plate and support, brackets on said fasteners, and wing nuts threaded to said fasteners against the brackets.
  2. A portière bracket comprising an attaching body portion having an opening for the passage of a securing element for fastening said portion to a support, and members

at the ends of the attaching portion extending forwardly from the front face thereof and of cylindrical form and each formed by bending over the respective terminal portions of the material from which the body portion is formed in its entirety, the margins of the overturned portions being mutually overlapped to avoid injury to portières suspended by the bracket.

In testimony whereof I affix my signature. 75
PETER JOSEPH FAGAN.
